J. B. WALKER.
 CLOSURE FOR JOINTS OF SECTIONAL COLLAPSIBLE CORES.
 APPLICATION FILED FEB. 27, 1915.

UNITED STATES PATENT OFFICE.

JOHN B. WALKER, OF BIRMINGHAM, ALABAMA.

CLOSURE FOR JOINTS OF SECTIONAL COLLAPSIBLE CORES.

1,154,079.

Specification of Letters Patent. Patented Sept. 21, 1915.

Application filed February 27, 1915. Serial No. 11,098.

To all whom it may concern:

Be it known that I, JOHN B. WALKER, a citizen of the United States of America, residing at Birmingham, in the county of Jefferson and State of Alabama, have invented certain new and useful Improvements in Closures for Joints of Sectional Collapsible Cores, of which the following is a specification.

10 My invention relates to a venting joint for the sections of collapsible cores of all types, and my object is to provide a novel type of joint which will permit of the free collapsing of the sections of a core barrel 15 while preventing the sand from interfering with the inward relative movements of the sections in collapsing.

Heretofore the joints of collapsible cores have been protected either by inserting a 20 wooden or metal strip into the joint to substantially close it while the core is being rammed and, after pouring, either removing the metal strip or burning out the wooden strip to relieve the core barrel and 25 permit its collapse; or the core sections have been so connected to a core plunger or bar that one or more sections are drawn in advance of the others, but in this latter construction the meeting edges of the sections 30 were either brought into engagement during the ramming of the core, or their joint was closed by a metal or wooden strip in the manner above described.

There are serious objections both structurally and economically to the use of the means as above described for closing the joints of collapsible core barrels and the object of my invention is to devise a joint construction which would avoid the objections to the above constructions; which would require no differential or timed relative movements of the core barrel sections; and which would require no insertion or removal of a filling means into the joints. 45 Obviously the preferred arrangement is one in which the joint closing devices are carried by and permanently attached to or integral with the core barrel sections so that no separate manipulation or attachment of the joint closing devices is required and they will move freely with the core barrel sections as they are expanded or contracted.

50 Where my invention is applied to the making of cores for ingot molds and heavy hollow castings of that character which it is desirable to ram upon a jarring machine, the

advantage of having the joint closing devices permanently attached to the core barrel and the sections of the latter held rigidly expanded by the core plunger, is of great importance, because the provision of any loose or lost-motion connection between the plunger and any one of the core barrel sections to permit it to collapse in advance of the other sections would be a fatal defect when rammed on the jarring machine.

The principles of construction underlying my improved joint closure makes it available for all types of collapsible cores regardless of the character of the article to be 70 molded thereabout and though I have illustrated it as applied to an ingot mold core, I do so without intention to thereby limit myself to any particular type of core barrel.

Referring to the accompanying drawings 75 which illustrate my invention: Figure 1 is a corner elevation of an ingot mold partly broken away and illustrating the sections in expanded position ready to be rammed. Fig. 2 is a cross sectional view of Fig. 1. 80 Fig. 3 is an enlarged sectional view of a cover showing the adjacent barrel sections expanded; and Fig. 4 is a view similar to Fig. 3 and illustrating the manner in which the core barrel sections clear themselves of 85 the sand at a corner for removal therefrom. Fig. 5 is an enlarged fragmental side view of the joint parts.

Similar reference numerals refer to similar parts throughout the drawings. 90

Referring to the illustrative embodiment of my invention shown in the drawings, I form the core barrel of two similar side sections 1 and two similar end sections 2, and I connect the several sections to a central plunger or bar 3 by means of toggle links 4 which are pivotally connected at their inner ends to the plunger in the manner described in my Letters Patent No. 997,027, or in any other suitable manner, 100 and at their outer ends these links are pivotally connected to lugs 5 on the inner walls of the several sections. The plunger has a shoulder (not shown) near its lower end which is adapted to engage the drag 6 and the lower end of the plunger projects below the drag and is perforated to receive a locking wedge key 7. The plunger is also perforated at its upper end to receive a wedge key 8 by means of which a top retaining plate 9 is wedged down upon the expended core barrel sections. This construction of 105 110

the core barrel is similar to that described in my said Letters Patent, but, as hereinbefore stated, may be widely varied according to the use for which the core barrel is designed.

In describing the corner joint in its preferred embodiment it will be noted that the edges of the solid plates or core barrel sections 1 and 2 are substantially spaced, providing what would be a wide joint of several inches in large ingot molds except for the means for closing the joint which will now be described. Along each inside corner edge of the sections 1 I provide an equidistantly spaced series of fingers 10, the outer faces of which along each edge lie in a plane inclined inwardly at an acute angle to the plane of the outer face of the section 1. The outer ends of these fingers 10 stand opposite the side margin of the inner face of the side sections 2 but are spaced therefrom, when the barrel is expanded, a substantial distance, say about an inch (see Fig. 3). The barrel sections 2 are provided along their inside corner edges with fingers 11 which are similar to the fingers 10 but are staggered with relation thereto so as to come opposite the spaces between the fingers 10. The fingers 11 lie in a plane inclined inwardly at an acute angle to the outer face of the sections 2 so as to stand substantially parallel with but outwardly spaced from the plane of the adjacent fingers 10. It will be noted that the ends of the fingers 11 stand opposite the end edges 12 of the sections 1 and are spaced therefrom substantially the same distance that the ends of the fingers 10 are spaced from the sides 2. Also the inner faces 13 of the fingers 11 are preferably inclined to correspond with the inclination of the outer faces of fingers 10. In my preferred arrangement the space between the fingers on a section is greater in width than the width of the fingers 10 or 11 so that when the sections of the core barrel are in expanded position ready to receive the sand, a clearance is provided by the alternating or staggered arrangement of the fingers 10 and 11 in each joint which forms an irregular or zig-zag venting space which is continuous throughout the length of the joint and is preferably of uniform width. Moreover this clearance is increased by the extent that the fingers 11 are spaced outwardly beyond the plane of the fingers 10. The clearance as thus provided can be as great as under good practice is considered safe for holding the sand. The fingers as shown taper in thickness from the barrel section outwardly, and all fingers are equal in size and preferably of narrow width. After the sand has been rammed about the core barrel, as shown in Fig. 3, the collapsing operation of the core barrel is as follows: By releasing the plunger 3 the core

sections are free to move inwardly under the contraction of the casting and in doing so the core barrel sections all move inwardly, the fingers 11 on the end sections 2 moving inwardly and as shown in Fig. 3, acting to 70 break away the sand between their inner tapered ends and the straight shoulder 12 on the sections 1 by forcing it into the open space in the sand core or coating left behind the receding sections 1. The only sand 75 which can prevent the free collapse of the core barrel is that which may collect between the fingers 11 and the end edges 12 of the section 1 and as this sand is readily broken out in the manner described, the 80 barrel is free to collapse, it being obvious that no sand can collect between the fingers 10 or the fingers 11, and if it does it would not interfere with the collapsing operation as these fingers never interlock and in fact 85 the space between the plane of the outer faces of the fingers 10 and of the inner faces of the fingers 11 increases as the core collapses. These fingers 10 and 11 of each joint therefore present staggered devices preferably in different planes which co-act to form a ventilating joint closure which will effectively hold the sand during the ramming of the core.

The advantage of making the fingers 10 95 and 11 relatively narrow is that I thereby increase the venting clearance in the joint and I obtain a strong corner for the core barrel without permitting any substantial packing of the sand between the fingers 11 100 and the shoulder 12. The width of the fingers may be increased within the scope of my invention but not beyond the point where sufficient sand can pack between the shoulder 12 on one side and the adjacent edge of a 105 section 2 and its fingers 11 on the other side, to interfere with the collapsing of the core barrel or weaken the corners of the core.

Inasmuch as I claim to be the first to successfully obtain by permanently attached 110 means a venting closure of the collapsible core barrel joint, I desire to claim the same broadly without being limited to the details of construction as hereinbefore described in their preferred embodiment.

Having thus described my invention, what I claim as new and desire to secure by Letters Patent, is:

1. In a joint for collapsible core barrels, a plurality of spaced inwardly inclined projections along the adjacent edges of the barrel sections, the projections on one core section being disposed opposite and adapted to partially close the spaces between the projections on the other core section, substantially as described.

2. In a joint for collapsible core barrels, a series of inturned fingers along each side edge of a barrel section, the fingers on one section edge being disposed opposite the

spaces between the fingers of an adjacent section edge, and the ends of the fingers on each section being spaced from the other section.

5 3. In a venting joint closure for collapsible cores, a series of fingers disposed along each core section edge at the joint, the fingers along the spaced edges of a joint being disposed in staggered relation and in 10 different planes.

10 4. The combination, with a sectional core and means to contract the sections toward each other, of a venting joint closure for the sections when expanded formed by a series 15 of spaced fingers, the fingers on one section being disposed opposite to and being narrower than the opposite spaces between fingers on the other section, and one set of fingers being disposed to the outside of the 20 other set of co-acting fingers, substantially as described.

25 5. A joint closure for collapsible core barrels comprising two co-related sets of fingers which extend only part way across the joint when the barrel is expanded and are substantially of equal width and taper outwardly in thickness, the fingers of one set being disposed opposite to the spaces between the opposite set of fingers, substantially 30 as described.

35 6. A corner joint for collapsible core barrels comprising, in combination with the barrel sections, a set of spaced fingers along an edge of one barrel section, the outer face of which fingers lie in a plane inclined

slightly inwardly across the joint, a set of fingers carried by the other section edge and set inwardly from its outer edge to dispose their outer faces inwardly of the first mentioned set of fingers, the outer faces of said 40 latter set of fingers being inclined in a plane parallel with the plane of the inner faces of the other set of fingers and disposed opposite the spaces between the fingers of said latter set, substantially as described. 45

7. In a corner joint for collapsible core barrels, the combination with the barrel sections, of a series of staggered fingers along the adjacent edges thereof, the fingers being inwardly inclined and outwardly tapering in 50 thickness and of relatively narrow uniform width and having their ends spaced from the opposite section when the core barrel is expanded, substantially as described.

8. In a joint closure for sectional collapsible cores, means to draw adjacent sections inwardly in lines at right angles to each other, fingers along the corner edges of the sections, the fingers on one section being opposite the spaces between the fingers on the 60 other sections and being spaced from said other section when in expanded position, substantially as described.

In testimony whereof I affix my signature in presence of two witnesses.

JOHN B. WALKER.
